UNITED STATES PATENT OFFICE

129,664

DESIGN FOR A TEXTILE FABRIC

Isidor Weinstein, New York, N. Y.

Application August 29, 1941, Serial No. 103,081

Term of patent 3½ years

To all whom it may concern:

Be it known that I, Isidor Weinstein, a citizen of the United States and resident of New York city, in the county of Kings, State of New York, have invented a new, original, and ornamental Design for a Textile Fabric, of which the following is a specification, reference being had to the accompanying drawing forming part thereof, and in which:

The figure is a plan view of a piece of textile fabric showing my new design.

The area bounded by the dot, dash lines is a repeat of the design.

I claim:

The ornamental design for a textile fabric, substantially as shown and described.

ISIDOR WEINSTEIN.
